UNITED STATES PATENT OFFICE.

WALTER J. WICKERS AND PATRICK M. FURLONG, OF BROOKLYN, NEW YORK.

PROCESS OF PRODUCING A GRADUATED SURFACE ON ETCHED OR ENGRAVED PRINTING-PLATES, &c.

1,250,404.

Specification of Letters Patent. Patented Dec. 18, 1917.

Original application filed January 22, 1902, Serial No. 90,811. Renewed March 14, 1917, Serial No. 154,905.

Divided and this application filed August 23, 1902. Serial No. 120,794.

To all whom it may concern:

Be it known that we, WALTER J. WICKERS and PATRICK M. FURLONG, citizens of the United States, residing in the borough of 5 Brooklyn, city of New York, have invented a Process of Producing a Graduated Surface on Etched or Engraved Printing-Plates, and Electrotype and Stereotype Duplicates Thereof; and we do hereby declare 10 that the following is a full, clear, and exact description of the invention, which will enable others skilled in the art to which it app- pertains to make and use the same.

Our invention consists of a method of 15 producing a graduated printing surface on relief or incised plates by lowering the surfaces carrying the lighter tones or raising those carrying the darker tones, or by using both these operations on one plate. To do 20 this we use an etched or engraved plate reduced in thickness from the standard heretofore used. We lay upon the back of this plate the ordinary printer's overlay, now used upon press cylinders, consisting of 25 sheets of papers or similar material laid together in graduated thicknesses according to the darkness or lightness of the tones of the picture, the greatest thickness opposite the darkest tone. We then place the print- 30 ing plate upon its face upon wax, or other similar semi-solid or plastic material, in a press, and exert pressure evenly on a plane surface upon the back of the plate and the overlay. By this pressure, the graduation 35 existing upon the overlay at the back of the plate, is transferred to the face of the plate, through the bending and swaging of the plate. This printing plate is now ready for use upon the printing press when backed in 40 the usual manner, without any preliminary "making ready."

The wax or other material into which the printing plate has been pressed is now impressed with an intaglio impression of the 45 printing plate, and constitutes a matrix upon which an electrotype shell may be deposited in the usual manner of the art.

If desired, we use this method conversely; i. e., we place upon the face of the printing 50 plate a reversed printer's overlay—one with the thickest parts over the lightest tones.

We place this reversed overlay upon the face of the printing plate, and place the plate face upward upon the wax or other semi-solid and liquefied material in a 55 press, and exert pressure evenly on a plane surface upon the face of the plate and overlay. By this pressure the graduation existing upon the overlay on the front of the plate, is transferred to the back through the 60 bending and swaging of the plate. The printing plate is now ready for use upon the printing press, when backed in the usual manner, without any preliminary "making ready."

It will be manifest that the wax, or analogous material, in which the printing plate is pressed, is of a plastic character; i. e., it can be molded, thereby permitting the formation of a replica of the plate there- 70 in, in contradistinction to material which is not plastic, but merely elastic.

This application is a division of our prior application Serial No. 90,811, filed Jan. 22, 1902, "Process of producing a graduated 75 printing surface on etched or engraved plates, electrotypes, etc."

In the drawing Figure A represents a cross-section through a printing-plate, having upon its surface four different tones of 80 shade, in sections marked *a*, *b*, *c*, and *d*. The section marked *a* is the darkest, being plain surface unrelieved by cutting; *b* is the next darker; *c* the next; and *d* the lightest. The depth of the cutting into the plate 85 is exaggerated, to make it more plain to the sight.

Fig. B represents a cross-section through an overlay composed of different sheets, cut away to correspond with the tones on the 90 printing-plate Fig. A.

Fig. C represents a power-press, *e*, with its face superimposed upon the back of the overlay *B*, which is in turn superimposed upon the back of the printing-plate *A* 95 which rests upon its face upon a bed of wax, *f*.

Fig. D represents a cross-section through the printing-plate after pressure has been applied in the press. The levels *a*, *b*, *c*, and 100 *d*, are now transferred to the face and correspond in position to the tones in those

sections, the darker tones being elevated above the others proportionately to their darkness. The difference in elevation of these different sections is exaggerated, to 5 make the effect of the process more plain.

We are aware of the English Patent No. 5,744 of 1901, granted to Eugene Albert of Munich, Bavaria, for "Improvements in the manufacture of printing blocks," and that 10 he transfers under his process the graduations of an overlay to a printing block by pressure. Our process, above-described, contains however, marked improvements over his patented process in the following 15 particulars:

1. The use of a thin plate of metal, thus permitting of the operation of the process without heating of the plate.

2. The use of a semi-solid liquefied material into which to press the plate, thus permitting a more perfect transference to the plate of the graduation existing upon the overlay or reversed overlay, as described.

3. The decrease in the time and expense 25 of preparing printing plates, owing to the readiness with which cold plates may be expeditiously pressed into the wax, with only moderate pressure.

4. By this improved process a graduated 30 printing surface is produced upon a printing plate, with acute angles in the planes of the metal at the edges of the various tones, upon ordinary plates; and also with the desired rounded edges upon vignetted plates.

35 What we claim as our invention is:

1. The method of preparing a graduated 40 printing surface which consists in applying to the back of a metallic plate an overlay of graduated thicknesses, placing said plate face downward upon plastic material, and subjecting the plate and overlay to pressure, thereby transferring said graduations of the overlay to the printing surface of the plate and simultaneously therewith producing in 45 the plastic material a matrix from which a replica of the printing surface can be produced.

2. The method of preparing a graduated 50 printing surface on a metallic plate which consists in applying to the back of a thin etched metallic plate an overlay of graduated thicknesses, the thicker portions of the overlay corresponding to the darker tones of the subject to be printed and the thinner 55 portions to the lighter tones of said subject, placing the plate face downward in plastic material, and subjecting the plate and overlay to pressure, whereby the graduated thicknesses of the overlay are adapted to 60 produce elevations and depressions in the printing surface of the metallic plate, and simultaneously producing a matrix in the plastic material.

3. The method of preparing a graduated

printing surface on a metallic plate which 65 consists in applying to the back of a thin metallic plate, provided on its face with an etched subject to be printed, an overlay of graduated thicknesses, placing said plate face downward in plastic material, and subjecting 70 the plate and overlay to pressure, whereby the graduations in thicknesses of the overlay act with different pressures on the plate and produce in the printing surface thereof elevations and depressions corresponding to the tones of the subject to be 75 printed.

4. The method of simultaneously producing 80 a printing surface on a metallic plate and a bas-relief matrix in plastic material 85 which consists in applying to the back of a thin metallic plate, having on its face an etched printing surface of a subject, an overlay of graduated thicknesses, placing the plate on the plastic material, and subjecting 90 the plate and overlay to pressure, thereby producing in the face of the plate permanent elevations and depressions and at the same time producing in the plastic material a matrix having a surface corresponding to the graduated surface of the metallic plate.

5. The method of preparing graduated 95 printing surfaces which consists in pressing an engraved plate, having an overlay of 100 graduated thicknesses applied to one face thereof, into a plastic material, thereby simultaneously transferring the graduations of the overlay to the engraved face of the plate and producing a matrix with a similarly graduated surface in the plastic material.

6. The method of producing graduated 105 printing surfaces which consists in providing on the back of an original engraved plate an overlay of graduated thicknesses, 110 pressing said plate face downward into plastic material, thereby transferring to the engraved face of the original plate graduations corresponding to the thicknesses of 115 said overlay and simultaneously therewith producing in the plastic material a matrix the surface of which is graduated similarly to the engraved surface of said original plate, and subsequently producing a replica 120 from the graduated surface of the matrix, whereby the replica is provided with a graduated printing surface corresponding to that of the original etched plate.

7. The method of producing graduated 125 printing surfaces which consists in providing on the back of an original engraved plate an overlay of graduated thicknesses, pressing said plate face downward into plastic material, thereby transferring to the engraved face of the original plate graduations corresponding to the thicknesses of 130 said overlay and simultaneously therewith

producing in the plastic material a matrix the surface of which is graduated similarly to the engraved surface of said original plate, and thereafter electrolytically depositing a metallic shell in contact with the graduated surface of the matrix, whereby said shell is provided with a printing surface

graduated correspondingly to the surface of the original plate.
